[57] CLAIM

The ornamental design for a combined table and floor lamp, as shown and described.

DESCRIPTION

FIG. 1 is a perspective view of a combined table and floor lamp showing my new design;

FIG. 2 is a side elevational view thereof;

FIG. 3 is a top plan view thereof;

FIG. 4 is an elevational view of a second embodiment of the combined table and floor lamp shown in FIG. 1;

FIG. 5 is an elevational view of a third embodiment of the combined table and floor lamp shown in FIG. 1;

FIG. 6 is an elevational view of a fourth embodiment of the combined table and floor lamp shown in FIG. 1;

FIG. 7 is a top plan view of a fifth embodiment of the combined table and floor lamp shown in FIG. 1; and

FIG. 8 is a fragmentary side elevational thereof.
